UNITED STATES PATENT OFFICE.

WILLIAM GEORGE ABBOTT, JR., OF WILTON, NEW HAMPSHIRE.

APPARATUS FOR CLEANING THE INTERIOR OF TUBULAR MEMBERS.

1,252,072.

Specification of Letters Patent.

Patented Jan. 1, 1918.

Application filed September 13, 1916. Serial No. 119,974.

To all whom it may concern:

Be it known that I, WILLIAM G. ABBOTT, Jr., citizen of the United States, and resident of Wilton, in the county of Hillsborough and State of New Hampshire, have invented new and useful Improvements in Apparatus for Cleaning the Interior of Tubular Members, of which the following is a specification.

10 This invention relates to apparatus for cleaning the interior of tubular members, and the apparatus is more particularly designed to clean the separator bowls of centrifuges, that is, instruments by which the 15 heavier constituents of a fluid such as blood corpuscles, bacteria, sediments, etc., may be separated by centrifugal action from the lighter portions.

In the use of centrifuges, it has been 20 found that a deposit of sediment collects on the walls of the separator bowls, and that, owing to the small size of these bowls, it is difficult to remove this sediment, especially in view of the fact that it forms a 25 hard cake due to the excessive centrifugal force driving the sediment outwardly against the walls. It has been proposed to remove this sediment by means of a small 30 instrument resembling a hoe, and such a device is fairly satisfactory for removing the bulk of the deposit. However, it is practically impossible to remove all the 35 sediment with an instrument of this character, and furthermore, there is the liability of scratching the interior surface of the bowl when attempting to do more than remove heavier deposits of material by means of a device of the character referred to.

40 The principal object of my invention, therefore, is to provide a device whereby the interior of the separator bowl of the centrifuge may be quickly and effectually cleansed without in any way marring the 45 interior surface of the bowl, it being highly desirable to maintain a perfectly smooth surface within the bowl inasmuch as only a surface of this kind can be thoroughly cleaned. It is a further object 50 of my invention to provide apparatus which will function both as a device for mechanically removing the deposit, and also as a device for introducing a cleansing fluid simultaneously with the mechanical opera-

tion of the device, whereby the two actions 55 are coöperative; that is, the fluid loosens the deposit and the mechanical cleaner or scraper removes the softened portions of the deposit in such a manner that the fluid can progressively reach successive layers of 60 the deposit in the most expeditious manner.

In the accompanying drawings,—

Figure 1 is a longitudinal section of a common type of centrifuge bowl; 65

Fig. 2 is an elevation of my improved apparatus;

Fig. 3 is an enlarged elevation of the forward end of the apparatus;

Fig. 4 is a horizontal central section of 70 the cleaning head (Fig. 3) and a portion of the supporting stem; and

Fig. 5 is a top view of the cleaning head and a portion of the stem, Figs. 4 and 5 being on an enlarged scale corresponding 75 to Fig. 3.

In the normal operation of a centrifugal machine the bowl 1 is ordinarily suspended in a vertical position by the screw projection 2. A cap, which is not shown, is 80 threaded upon the lower end of the bowl by means of the threads 3. This cap covering a hollow tip projection which is adapted to run in a wooden bushing in such manner as to steady the bowl. Suitably 85 placed below this tip is a nozzle which projects the liquid to be separated upwardly into the bowl. After passing into the bowl the liquid is thrown outwardly by centrifugal force and forms upon the inner 90 surface of the bowl a cylindrical layer of diminished density from the inside outwardly. When the liquid rises to the top of the bowl it discharges outwardly through the outlets 4 and 5, the lighter material 95 passing out through orifice 4 and the heavier material passing out through orifice 5. While only one outer orifice 5 is shown in the cross sectional view of Fig. 1, three or more of these outlets equally spaced around 100 the periphery of the bowl, are ordinarily provided.

Most of the solid material tending to deposit on the walls of the bowl is deposited at the entrance end, resulting in the formation of a tapering deposit indicated in Fig. 1 by the numeral 6. When this material fills up to the top of the bowl the ports 5

are finally covered and the machine must be stopped and cleaned. The most satisfactory means for performing the cleaning operation, of which I am aware, comprises the 5 apparatus now to be described.

The cleaning apparatus comprises a small tube 7, a cleaning head 8 and preferably a hose 9 through which steam, hot water or other cleansing fluid may be introduced to 10 the cleaning head. The cleaning head comprises three or more spiral ribs 10 uniformly spaced about the outer periphery of the head and each extending to such length that they overlap, as indicated, forming spiral 15 channels therebetween. The three ribs indicated generally as 10 in Fig. 2 are respectively indicated as 10^a, 10^b and 10^c in the enlarged Figs. 3, 4 and 5. The forward end of each rib is curved outwardly so that the 20 duct extending longitudinally therethrough will be directed forwardly and tangentially and the end of each rib is beveled off, as indicated at 20, in such manner that an opening 25 therein, communicating with the interior of the head, will be disposed in such manner that a jet of fluid passing outwardly therefrom will be projected along a line substantially tangent with the periphery of the head and making an angle of approximately 30 45° with the forward face of the head, as indicated in Figs. 4 and 5. The cleaning head may either be fixedly or rotatably mounted on the forward end of the tube 7. While the particular means of rotatably mounting the head on the stem forms 35 no part of my invention, I have illustrated a convenient means in Fig. 4, this means comprising an enlargement 21 on the end of the stem fitting into a flanged sleeve 22 which 40 may be brazed to the head 8. A handle 12 is preferably provided at the rear end of the tube 7 for operating the device in the manner now to be described.

The bulk of the solid deposit 6 is preferably pulled out by means of an instrument 45 resembling a hoe, as above mentioned. The cleaning device is then inserted into the bowl preferably to the full extent so that the head 8 and the jets 13 are brought approximately opposite to the ports 5. When the water or steam is turned on, the jets 13 wash away dirt that is collected in the ports and the water or steam escapes backwardly 50 through the channels between the ribs 10. When the bowl is rotatably mounted on the tube 7 the passage of the steam or water backwardly along the ribs 10 causes the cleaning head to rotate, and owing to the fact that the jets of water are thrown forwardly at an angle to the face of the cleaning head and in the proper direction, the action of the jets tends to increase the 55 rotary motion of the head. Thus, the whirling jets of fluid thoroughly remove all foreign 60 matter from the upper portion of the bowl 65

and the head is then slowly withdrawn and the lower portions of the tube are cleansed in the same manner.

The angular disposition of the ribs 10 is so related to the disposition of the apertures 70 11 that the rotary motion of the fluid, produced by the tangential components of the motion of the projected jets, is maintained as the fluid passes rearwardly along the ribs in escaping from the tubular member. Thus, 75 the two means for producing the whirling motion of the fluid act in conjunction and the cumulative action of the two agencies effects a thorough removal of the foreign matter deposited upon the inner surface of 80 the tubular member.

At times particles of material become wedged or packed into the outlet ducts 4 and 5 in such manner that the whirling jets of water or steam are insufficient to clear the 85 passage ways. In such cases the spiral ribs 10 are of particular utility inasmuch as the head 8 can be rapidly moved backwardly and forwardly as a plunger whereby considerable pulsating force can be applied to 90 the liquid in front of the cleaning head to clear the ducts 4 and 5. The diameter of the cleaning head measured to the outer periphery of the ribs 10 is preferably made only slightly smaller than the interior diameter 95 of the tube, whereby the head obstructs the major portion of the tubular passage within the bowl and may thus operate effectively as a plunger.

The ribs 10 are made equal in number to the jet openings 11 and the jet openings are spaced about the cleaning head in correspondence with the ribs, whereby the ribs and jets operate in conjunction. Obviously, the ribs 10 may also function as scrapers to remove the successive layers of deposit as they are softened and loosened by the action of the cleaning fluid. And when the head is rotatably mounted on the stem 7, the ribs serve to dislodge foreign matter as they rotate in proximity to the interior surface of the tubular member being cleaned. 100

While the ribs 10 are shown as being hollow this is not essential, it only being necessary to have some communication between the apertures 11 and the interior of the head 8. However, when the head is rotatably mounted on the stem it is desirable to have a short bend in the ducts near the apertures so that the jets of fluid will react more forcibly upon the head to cause it to rotate. 115

I claim:

1. Apparatus for cleaning the interior of tubular members comprising a supporting member, a cleaning head mounted on the supporting member at the forward end of the apparatus, the cleaning head having unobstructed fluid ducts directed forwardly and tangentially in the region of its periphery so as to project jets of fluid for 125

- wardly and tangentially from the cleaning head directly against the interior surface of the tubular member, and means for passing fluid through the fluid ducts.
5. 2. Apparatus for cleansing the interior of tubular members comprising a supporting member, a cleaning head mounted thereon, and angularly disposed ribs on the periphery of the cleaning head, the cleaning head
- 10 having apertures in the forward end thereof, the apertures communicating with the interior of the cleaning head and supporting member and opening at the front of said head so that fluid may be projected there-
- 15 through in advance of the ribs.
3. Apparatus for cleansing the interior of tubular members comprising a hollow support, a cleaning head on the forward end of the support, and overlapping ribs an-
- 20 gularly disposed on the periphery of the cleaning head, the forward end of the ribs having apertures communicating with the interior of the head, the apertures being so disposed as to project jets of fluid obliquely
- 25 to the face of the cleaning head.
4. Apparatus for cleaning the interior of tubular members comprising a supporting member, a cleaning head mounted on the forward end of the apparatus, the cleaning
- 30 head having unobstructed apertures in its forward end near its upper periphery and fluid ducts communicating with the apertures, and means for passing fluid through the fluid ducts, the ducts and apertures be-
- 35 ing directed forwardly and tangentially so that the fluid is projected in jets from the apertures both forwardly and tangentially with respect to the cleaning head directly against the interior surface of the tubular
- 40 member.
5. Apparatus for cleansing the interior of tubular members comprising a hollow sup-

the end of the support, and angularly dis-
posed ribs on the periphery of the cleaning 45
head, the forward end of the cleaning head
having apertures for introducing fluid to
the tubular member so that the fluid flow-
ing backwardly along the angularly dis-
posed ribs will cause the cleaning head to 50
rotate.

6. Apparatus for cleansing the interior
of tubular members comprising a hollow
support, a cleaning head rotatably mounted
on the forward end of the support, and an-
gularly disposed ribs on the periphery of 55
the cleaning head, the cleaning head having
apertures in the forward end thereof, the
apertures being disposed in such manner
that fluid escaping therefrom will cause the 60
head to rotate in one direction and the ribs
being so disposed that fluid flowing back-
wardly along the ribs will tend to produce
rotation of the head in the same direction.

7. Apparatus for cleansing the interior 65
of tubular members comprising a support-
ing member, a cleaning head mounted there-
on, and angularly disposed ribs on the pe-
riphery of the head, the cleaning head hav-
ing apertures in the forward face thereof 70
communicating with the interior of the
head, the apertures being so disposed as to
project a jet of fluid in such manner as to
produce a rotary movement of the fluid
within the tubular member, the angular dis- 75
position of the ribs being such as to main-
tain the rotary movement of the fluid in
the same direction as the fluid passes rear-
wardly along the ribs.

Signed by me at Wilton, New Hampshire, 80
this 9th day of September 1916.
